DISPENSERS FOR CIGARETTES AND SIMILARLY SHAPED OBJECTS

Harold Leopold Rink, Bridport, Dorset, and Reginald Farran Spence, near Bridport, Dorset, England

Application August 13, 1954, Serial No. 449,579

Claims priority, application Great Britain August 18, 1953

4 Claims. (Cl. 221—203)

This invention concerns improvements in or relating to dispensers for cigarettes and similarly shaped objects (all hereinafter included in the term "cigarettes") of the kind comprising a hopper to receive the cigarettes and to deliver them to a rotatable delivery element or roller (hereinafter referred to as a "roller") located at the lower part of the hopper and which is adapted to receive the cigarettes from the hopper and, on the roller being rotated relatively to the hopper, to dispense the cigarettes in small numbers and preferably one at a time.

Dispensers of the kind referred to have been previously proposed in which the cigarette delivered by the roller rolls down a chute from which the user removes it, or into the palm of the hand placed below the roller, the cigarette remaining substantially parallel to the axis of the delivery roller whilst being discharged.

An object of this invention is to provide an improved cigarette dispenser which presents the discharged cigarette to the user in a readily receivable form.

According to this invention there is provided a cigarette dispenser of the kind specified and wherein are provided ejecting means adapted automatically to cause a cigarette being delivered by the roller of the dispenser to be moved, on reaching the or a delivery position, relatively to, and transversely of the axis of, the said roller in such a manner that one end portion of the cigarette is moved away from the roller and ejected from the dispenser whilst the other end portion of the cigarette remains in the dispenser, the cigarette thus presenting one end to an intending user to facilitate his withdrawal of the cigarette from the dispenser.

Conveniently means are provided whereby that end portion of the cigarette which temporarily remains in the dispenser is lightly gripped therein.

According to a further feature of the invention the cigarette ejecting means may be so constructed that the said ejected end portion of the cigarette moves from the roller transversely of the axis of the latter during the ejection of such cigarette end portions, whereby the cigarette assumes a position in which it is inclined to, and diverges from, the roller from that end portion remaining in the dispenser to its other end.

The said roller is preferably so constructed that at least that end portion of the cigarette which is temporarily to remain in the dispenser after the ejection from the latter of the other end portion of the cigarette is, during its movement towards the delivery position, unsupported by, or is free to move inwardly with respect to, the roller, and wherein the said ejecting means are adapted to exert inward pressure on the said unsupported or inwardly movable end portion of the cigarette at least when the latter reaches the delivery position, thereby to push the unsupported or inwardly movable end portion of the cigarette inwardly with respect to the said roller, the cigarette rocking see-saw fashion in the roller and the opposite end portion of the cigarette thus being projected outwardly from the dispenser.

That end portion of the cigarette temporarily remain-

2

ing in the dispenser is conveniently lightly gripped between the said roller and the said ejecting means.

The said roller will preferably be in the form of a cylinder having longitudinal cigarette locating means provided by at least one longitudinal groove to receive from the hopper one cigarette at a time for advancement to the said delivery position and desirably will have a plurality of such longitudinal grooves all parallel to the axis of the roller and equi-angularly spaced around the circumference of the latter. The roller could, however, be of other forms; for instance it may comprise a spindle having outwardly extending longitudinal ribs defining pockets or grooves therebetween, or it could comprise a plurality of peripherally notched or grooved discs or wheels on a common spindle.

It is preferred to arrange the groove or grooves or equivalent means, all hereinafter referred to as "grooves," in the roller so as to have the longitudinal medial plane or planes thereof tangential to an imaginary cylindrical surface concentric with the axis of the roller.

Preferably the said roller is substantially wholly enclosed in the lower part of the hopper, the roller working in a substantially cylindrical and closely-fitting housing formed on, or attached to, the lower part of the hopper and having a longitudinal delivery slot parallel to the axis of the roller and through which a cigarette protrudes when delivered by the roller.

The said ejecting means preferably comprise a spring element which may be in the form of a spring finger normally held out of contact with a cigarette in the roller but being released to press the unsupported or inwardly movable end portion of the cigarette inwardly when the cigarette reaches its delivery position.

In order to leave one end portion of the cigarette unsupported or inwardly movable in the roller as it is moved by the latter to the delivery position as above described, the roller may be recessed inwardly at one end. Thus the roller conveniently has at least one longitudinal groove, as aforesaid, for picking up a cigarette from the hopper and for conveying it alone to the delivery position of the dispenser, and this groove is preferably so formed as to support the cigarette along its whole length up to a position short of one end of the cigarette where the groove becomes progressively deeper to its outer end so as to leave the cigarette unsupported over this ramp-like base surface of the groove whereby, when inward pressure is applied to the unsupported end of the cigarette, this end swings inwardly and the other end of the cigarette swings outwardly with respect to the roller, the junction of the inner end of the progressively deepened part of the said groove with the remainder of the groove constituting a fulcrum for the cigarette.

Alternatively, that end portion of the cigarette temporarily to remain, in the dispenser may be supported in the roller by a light spring or other resilient support which recedes under the action of the ejector means, thus leaving that end portion of the cigarette inwardly movable.

It will be appreciated that, when the roller comprises grooved discs or wheels on a common spindle or when it is of the other forms as hereinbefore described, the longitudinal cigarette locating means are so arranged that that end portion of the cigarette which is temporarily to remain in the dispenser is unsupported or inwardly movable at the delivery position.

The cigarette is lightly gripped between the ejecting means and the roller and the ejecting means thus also serve temporarily to retain the cigarette in the roller.

The retained end of the cigarette and the said ejecting means may be shielded by a hood provided on a portion of the dispenser housing extending over or around the said roller.

Means may also be provided for causing a jiggling or vibration of the cigarettes in the hopper, thereby to reduce or prevent arching of the cigarettes in the hopper and to facilitate the entry of a cigarette or cigarettes from the hopper into the longitudinal groove or grooves of the roller as this rotates. Such means may comprise a plate, or false wall plate, in the said hopper which is periodically moved relatively to the opposite wall of the hopper thereby to disturb the cigarettes in the latter. Alternatively, or as well, means may be provided for causing a rising or falling or jiggling or vibration of the roller as it rotates which likewise serves to reduce or prevent arching of the cigarettes over the roller and within the hopper.

Preferably means are also provided for limiting the rotation of the roller to rotation in the delivery direction only.

It is also desirable to provide means whereby the roller may not, during the dispensing of a cigarette, be accidentally forced past the delivery position with resulting damage to the cigarette being dispensed.

A cigarette dispenser according to the invention is particularly suitable for use in motor cars and other vehicles and places where one-handed dispensing of a cigarette is desirable, the cigarette being ejected at one end only ready for removal from the dispenser when the opportunity arises but meanwhile being lightly gripped or held at the other end in the dispenser so as to avoid the likelihood of the cigarette falling out of the dispenser.

In order that the invention may be more readily understood two embodiments of the same will now be described by way of example with reference to the accompanying drawings in which:

Figure 1 is a perspective view of a cigarette dispenser constructed in accordance with this invention and showing a cigarette ejected ready for removal by the user.

Figure 2 is an end elevation (looking from the left of Figure 1), of the cigarette dispenser shown in Figure 1.

Figure 3 is a section on line III—III, Figure 4.

Figure 4 is a horizontal section on line IV—IV, Figure 3.

Figure 5 is a rear elevation partly broken away of the dispenser shown in Figures 1 to 4.

Figure 6 is a side elevation of the dispenser shown in Figures 1 to 5 and illustrates one method of attaching it to the dashboard of a motor car or the like.

Figure 7 illustrates an alternative method of attaching the dispenser shown in Figures 1 to 5 to a wall, a windscreen of a car or the like.

Figure 8 is a transverse fragmentary cross-sectional elevation showing a slight modification of the cigarette dispenser shown in Figures 1 to 5.

In the first embodiment of the invention, illustrated in Figures 1 to 5 of the drawings, the dispenser comprises a casing 1 having an approximately cylindrical, hollow, horizontal housing 2 at the lower part thereof in which is coaxially mounted a roller 3 having longitudinal cigarette locating means which in this instance are in the form of grooves 4 in its external periphery and which is capable of being rotated in, whilst being peripherally confined by, the housing 2, and a part constituting a hopper 5 extending upwardly from, and communicating with, an elongated opening with, the housing 2 and of approximately rectangular cross-section in plan.

The rear wall 6 and the lower and internal convergent portion 7 of the front wall of the hopper 5 converge downwardly towards the roller 3, the internal convergent portion 7 extending to a position closely adjacent the vertical plane containing the axis of the roller 3, and the internal surface of the rear wall 6 meeting the inner surface of the housing 2 at 8, a position about 60° rearwardly of the said vertical plane.

The lengths of the hopper 5, the housing 2 and the roller 3 are slightly in excess of the length of the longest cigarette that the device is to dispense and the hopper

5 is intended to receive the cigarettes such as those indicated at 9, Figure 3, in positions parallel to the axis of the roller 3. To enable cigarettes to be inserted in the hopper 5, the upper end of the same is provided with a filling opening or slot 10 and a hinged cover 11 therefor. Conveniently the upper end of the hopper is of semi-cylindrical form and the filling opening or slot 10 is provided in the front part of the top portion of the hopper for the admission of cigarettes to the latter and the cover 11 is of approximately quadrantal form and is furnished at its ends with sector shaped lugs 12 pivoted to the ends 13 and 14 of the hopper respectively, this cover 11 being capable of being swung rearwardly in the direction of arrow A, Figure 3, when it is desired to expose the filling opening or slot 10. To facilitate the raising of the cover 11, a notch 26 is provided in the upper edge of the front wall of the casing 1 to receive the nail of the finger or thumb of the operator.

The back of the hopper 5 is conveniently provided externally with a central lug 15 to which is screwed a downwardly convergent wedge-shaped plate 16 adapted releasably to engage in downwardly convergent channels 17 in a triangular fixing plate 18. The latter is adapted to be attached to the dashboard of a motor car or like supporting surface either directly by screws 19, as shown in Figure 6, or by suction elements 21 bolted to the plate 18, as shown in Figure 7.

Conveniently the hopper 5 and the approximately cylindrical housing 2 are formed as mouldings, preferably from plastic, such as thermosetting plastic, and are made in two halves or parts meeting in a vertical plane passing through the axis of the housing 2. The lower parts of the two halves or parts are secured together by screws 22 whilst their upper parts are secured by the engagement of looped or eyelike ends 23 of the lugs 12 around the two halves 24 and 25 of vertically split pivot projections each formed one on the front half or part and the other on the rear half or part of the casing 1 and over which the lugs 12 are sprung when applying the cover 11 to the casing 1.

In the lower part of the housing 2 for the roller 3 is provided a longitudinal slot 27, see Figures 3, 4 and 8, through which cigarette dust or the like can leave the housing 2 so as not to impede the rotation of the roller 3.

The longitudinal grooves 4 of the roller 3 are spaced equi-angularly around the circumference of the roller 3 which is conveniently made as a plastic moulding. The longitudinal grooves 4 are not radial but are preferably offset from the radii of the roller so that their longitudinal medial planes 28, see Figure 2, are substantially tangential to an imaginary cylindrical surface 29 which is coaxial with the axis of the roller and on which lie the rounded bottoms 30 of the grooves, the arrangement thus being such that the rear (rotationally speaking) wall 31 is shallower than the front wall 32 of each of the longitudinal grooves 4 and has a somewhat undercut appearance in end view.

Each of the longitudinal grooves 4 of the roller 3 is capable of receiving a cigarette entirely within it and within the peripheral bounding surface of the roller 3, the cigarette passing sideways-on, that is, by movement in a direction transverse to its length, to the longitudinal grooves at the rear of the hopper as clearly shown in Figure 3. The cigarette is directed by the downwardly and forwardly inclined back wall 6 of the hopper 5 into the longitudinal groove 4 when the rear wall of the latter lies adjacent to the said back wall 6, as shown in Figure 3, the walls of each longitudinal groove 4 and the said back wall 6 of the hopper 5 being substantially parallel in this position of the roller.

Over one end portion thereof, each of the said longitudinal grooves 4 is inwardly recessed so that its depth progressively increases towards the nearest end of the roller, as shown at 33, Figure 4. Thus, when a cigarette lies in a longitudinal groove 4 with its axis parallel to

the axis of the roller 3, the cigarette is supported for the major part of its length by the base of the longitudinal groove 4, but, over that end portion of the cigarette lying opposite the recessed part 33 of the groove, the cigarette is unsupported so that, if inward pressure is applied to this end portion of the cigarette, the cigarette will rock see-saw fashion in the roller and the opposite end of the cigarette will be projected outwardly from the dispenser.

Each end of the roller 3 is provided with a coaxial outwardly extending trunnion 34 which is journaled in the corresponding end wall of the housing 2. The outer ends of the trunnions 34 project through and beyond the end walls of the housing 2 and are then each provided with a square-section portion 35 on to which an operating wheel 36 is fixed by a screw 37. Each of these wheels 36 is peripherally inwardly scalloped so as to produce a number of radial spokes or protuberances 38 corresponding in number and in position to the longitudinal grooves 4. Moreover, the major part of the periphery of each of the wheels 36 is enclosed in an annular overhanging guard 39 so that all except one of the spokes or protuberances 38 are enshrouded. The guard 39 is formed integrally with the ends of the housing 2, there being a segmental gap 40 in this guard 39 at the front of the dispenser and over an arcuate length of the guard sufficient to enable each of the said wheels 36 to be rotated by one of its forwardly directed spokes or protuberances 38 far enough to dispense one cigarette at a time and to expose the next spoke or protuberance 38 of the wheel 36 ready for operation of the roller 3.

At the end of each delivery operation of the roller 2 the spoke or protuberance 38 by which the roller 3 was rotated to dispense the cigarette will pass into the guard 39, see Figures 1 and 2, so that the wheel 36 cannot be rotated further by pressing on this spoke or protuberance. Thus the entry of the spokes or protuberances one by one into the guard 39 limits the extent to which the roller 3 can be rotated by each spoke or protuberance, and the accidental movement of the roller 3 past its delivery position will be avoided.

The operating wheels 36 or their spokes or protuberances 38 may be knurled or serrated perimetrically, as shown in Figures 1, 2 and 5, to facilitate their operation.

In the front of the housing 2 and mainly above the horizontal plane containing the axis of the roller 3 is provided a horizontal delivery slot 41 extending from one end almost to the other end of the housing 2 but having, over the end of the delivery slot 41 adjacent that portion of the roller 3 where the said longitudinal grooves 4 in the roller are recessed, an outwardly transversely bowed hood 42 which extends for a short distance along the delivery slot 41 from the said end. Thus, when a cigarette is in the delivery position opposite the delivery slot 41, one end portion of the cigarette is concealed by the hood 42, whilst the remainder of the cigarette is exposed to view.

Within the casing 1 of the dispenser and at that end thereof having the hood 42, ejecting means are located in the form of a vertical pendent leaf spring or finger 43, secured, as by a screw 44, to the inner surface of the front wall of the hopper 5, the lower part of the leaf spring or finger 43 extending downwardly in a channel 45, defined by the hood 42, on to the periphery of the roller 3, the lower part 46 of the leaf spring or finger 43 being substantially rectilinear and terminating slightly above the level of the lower edge of the delivery slot 41.

Thus, as the roller 3 rotates forwardly and carries a cigarette, such as the cigarette 48, from the rear part of the lower end of the hopper 5 into registration with the delivery slot 41, the cigarette is brought into engagement with the lower end portion 46 of the leaf spring 43. The portion 46 presses the engaged end of the cigarette rearwardly, so that the cigarette pivots on the

fulcrum 47, Figure 4 (formed at the junction of the main part of the base of the groove 4 in which the cigarette is located and the inwardly and progressively inclined inset portion 33 of the groove where that end portion of the cigarette engaged by the spring or finger 43 is normally unsupported whilst in the groove), the opposite end portion of the cigarette being consequently projected outwardly see-saw fashion, through the slot 41 in the direction of arrow B, Figure 4, whilst the end of the cigarette engaged by the leaf spring or finger 43 is gripped lightly between the latter and the roller 3 until pulled endwise therefrom by the intending user who grasps the projected end portion of the obliquely and outwardly directed cigarette.

To achieve the forward oblique ejection of the cigarette 48 through the delivery slot 41 of the dispenser 1, the lower end 46 of the leaf spring or finger 43 is prevented from engaging the cigarette 48 until the latter has been registered with the delivery slot 41. Thus the lower end 46 of the leaf spring or finger 43 rides upon a cylindrical part 49 of the external periphery of the roller 3 in advance of the groove thereof next to deliver a cigarette until this groove has registered with the delivery slot 41 when the lower end 46 of the leaf spring or finger 43 is released by the roller 3 and springs inwardly on to the cigarette 48. The unsupported end of the latter is thus pushed inwardly with respect to the roller 3, the extent of inward movement of the leaf spring or finger 43 being limited when no cigarette is in the groove by the engagement of the cranked portion of the leaf spring or finger 43 adjoining the part 46 of the latter with the outer end of the rear wall 31 of the longitudinal groove 4 into which the lower end 46 of the leaf spring or finger 43 has moved, as illustrated in Figure 2.

The lower end 46 of the leaf spring or finger 43 is twisted out of the plane of the remainder thereof, so as to be inclined to the longitudinal central medial plane of the dispenser as clearly seen from Figures 3 and 4.

To facilitate the rapid entry of the lower end 46 of the leaf spring or finger 43 into the longitudinal grooves 4 as these are brought seriatim into registration with the delivery slot 41, the outer corner 52 of the front wall of each longitudinal groove 4 is rounded off.

The leaf spring or finger 43 also serves yieldingly to restrain the roller 3 of the dispenser from rotating accidentally or from turning, at each operation thereof, through an angle exceeding that between two successive cigarette longitudinal grooves 4, i. e. the angular movement required to deliver one cigarette.

The leaf spring or finger 43 has an upward extension 50, the upper end 51 of which serves to engage the inner surface of the cover 11 of the dispenser to prevent this cover accidentally opening and, if desired, the cover may have a protuberance in its inner side to co-operate to this end with the upper end 51 of said leaf spring extension 50.

In order to vibrate or jig the cigarettes in the hopper 5 and keep them mobile, the hopper 5 is provided with a false back wall in the form of a U-shaped plate 53 formed of springy sheet material such as 36 S. W. G. hard brass sheet, and secured at its upper part to the back of the hopper 5 by screws 54. The lower part of the plate 53 normally lies against the back of the hopper 5 and this lower edge of the plate 53 is located just above the adjacent part of the periphery of the roller 3.

From the lower part of each side edge of the said plate 53, an integral lug 55 projects forwardly at right angles to the plate, each lug 55 lying between one end of the groove-provided part of the roller 3 and the adjacent side or end wall of the dispenser casing 1. Each of said lugs 55 is conveniently of triangular form in side elevation and has at its forward end a dependent detent or pawl 56 which co-operates with a toothed wheel 57 fixed one on each end of the roller 3, this wheel having as many teeth 58 as there are longitudinal

grooves 4 in the roller 3 and each tooth being located just in front of the front wall 51 on each longitudinal groove 4.

It will thus be seen that, as the roller 3 is rotated, the detents 56 of the plate 53 are repeatedly acted upon by the teeth 58 of the toothed wheels 57 thereby to pull the lower part of the plate 53 forwardly to disturb the cigarettes (and particularly the cigarettes arched over the roller 3) in the hopper 5 and to push them slightly in a forward direction, the plate 53 then suddenly being released to spring back to its original position and relieves the cigarettes of forward pressure. Thus the liability of the cigarettes arching is reduced to a minimum and the cigarettes are kept mobile so as to pass one after another into the longitudinal grooves 4 of the roller 3.

Moreover, the co-operation of the teeth 58 with the plate 53 pawl and ratchet fashion limits the rotation of the roller 3 to a forward direction only.

In the alternative embodiment of the invention shown in Figure 8, the vibration or jiggling of the cigarettes is obtained by vibrating the roller 3 in a vertical direction as it rotates. To this end the trunnions 34 of the roller 3 are journaled in vertical slots 59 in the end walls of the housing 2, these slots permitting the roller 3 to rotate and also to move up and down to a limited extent, whilst restraining the roller 3 against movement forwardly or rearwardly.

To ensure that the roller 3 is vertically jiggled or vibrated periodically as it rotates, an upwardly projecting cam ridge 60 is provided near each end of the housing 2 at the lower part thereof so that, as the roller 3 rotates, each peripheral cylindrical part 49 thereof located between a pair of rotationally succeeding longitudinal grooves 4 will ride along the cam ridge 60 to cause the roller 3 to be raised to a small extent in the housing 2 after which the roller 3 will be sharply dropped in the housing 2, this occurring as many times in the rotation of the roller 3 as there are longitudinal grooves 4 therein and disturbing the cigarettes resting on the upper part of the roller 3 at any particular moment and so preventing these cigarettes arching over the top of the roller 3. If desired spring means, not shown, may be provided for pressing the roller 3 downwardly.

It is thus seen that the cigarette dispenser of this invention has a pleasing appearance and may easily be operated one-handedly to dispense cigarettes one at a time, each cigarette at delivery being projected outwardly from the dispenser so that it may easily be grasped one-handedly by the user but at the same time being prevented from falling from the dispenser since one end portion is lightly gripped in the latter.

We claim:

1. A cigarette dispenser comprising a hopper to receive the cigarettes; a housing at the lower part of said hopper and communicating with the latter through an elongated opening permitting cigarettes to pass sideways from the hopper to the housing; a roller rotatably mounted in, and peripherally confined by, said housing immediately below and parallel to said elongated opening, said roller having a plurality of longitudinal grooves arranged at equi-angularly spaced intervals around its periphery and each adapted to register periodically with said elongated opening and alternately with a delivery slot provided in the peripheral wall of said housing at a position rotationally in advance of said elongated opening and alongside said roller, all of said grooves being recessed inwardly at one and the same end so that at this end a cigarette lying in the groove is inwardly movable with respect to the roller; an operating member for rotating said roller in said housing; a radial spoke on said operating member for each of the longitudinal grooves in the roller; a guard on said housing and enshrounding all except one of said spokes at a time so that only one can be grasped to operate the roller; a plate forming a

15 false wall for the back of the said hopper; tooth means on said roller adapted to co-operate, as said roller rotates, with said plate to move the latter relatively to the back of the hopper so as to disturb the cigarettes in the latter, said tooth means also co-operating with said plate pawl-and-ratchet-fashion to limit the rotation of the said roller to rotation in the delivery direction only; and a spring ejecting finger in said housing opposite that end portion of said roller at which the recessed ends of said grooves are located and adapted to bear on the inwardly movable end portion of a cigarette lying in a groove when that groove registers with the said delivery slot so as to urge the inwardly movable end portion of the cigarette inwardly thereby to cause the other end of said cigarette to move outwardly to the outside of said housing.

2. A cigarette dispenser comprising a hopper to receive the cigarettes; a housing at the lower part of said hopper and communicating with the latter by an elongated opening permitting cigarettes to pass sideways from the latter into the housing; a roller rotatably mounted in said housing immediately below and parallel to said elongated opening; cam means for slightly raising the roller periodically in said housing as the roller rotates to jig the cigarettes in the said hopper to keep them freely dischargeable from the latter through said elongated opening, said roller being peripherally confined by said housing and journaled therein so as to be free for a limited rising and falling movement in the housing and said roller having a plurality of longitudinal grooves arranged at equiangularly spaced intervals around its periphery and parallel to its axis of rotation, each said groove being adapted alternately to register with said elongated opening and with a delivery slot provided in the peripheral wall of said housing at a position rotationally in advance of said elongated opening, parallel to the latter and alongside said roller, one end portion of each of said grooves of the roller being inwardly recessed so that the portion of the cigarette located in such a groove and lying in front of said recess is unsupported and free for inward movement when the groove registers with said delivery slot and the remainder of the cigarette is freed for outward movement with respect to said roller; and a spring ejecting finger in said housing opposite the recessed ends of said grooves and adapted to bear successively on the inwardly movable end portions of cigarettes in said grooves as the said roller is rotated and, when each such cigarette registers with the said delivery slot, to urge the inwardly movable end portion of the cigarette inwardly thereby to cause the remainder of the cigarette to move outwardly from said roller, through said delivery slot, to the outside of said housing.

3. A cigarette dispenser comprising a hopper to receive the cigarettes; a housing at the lower part of said hopper and communicating with the latter through an elongated opening permitting cigarettes to pass sideways from the hopper to the housing; a roller rotatably mounted in, and peripherally confined by, said housing immediately below and parallel to said elongated opening, said roller having a plurality of longitudinal grooves arranged at equi-angularly spaced intervals around its periphery and each adapted to register periodically with said elongated opening and alternately with a delivery slot provided in the peripheral wall of said housing at a position rotationally in advance of said elongated opening and alongside said roller, all of said grooves being recessed inwardly at one and the same end so that at this end a cigarette lying in the groove is inwardly movable with respect to the roller; operating means for effecting rotation of said roller; a plate forming a false wall for the back of the said hopper; tooth means on said roller adapted to co-operate, as said roller rotates, with said plate to move the latter relatively to the back of the hopper so as to disturb the cigarettes in the latter, said tooth means also co-operating with said plate pawl-and-ratchet-fashion

thereby to limit the rotation of the said roller to rotation in the delivery direction only; a spring ejecting finger in said housing opposite that end portion of said roller at which the recessed ends of said grooves are located and adapted to bear on the inwardly movable end portion of a cigarette lying in a groove when that groove registers with the said delivery slot so as to urge the inwardly movable end portion of the cigarette inwardly thereby to cause the other end of the said cigarette to move outwardly to the outside of said housing.

4. A cigarette dispenser comprising a hopper to receive the cigarettes; a housing at the lower part of said hopper and communicating with the latter through an elongated opening permitting cigarettes to pass sideways from the hopper to the housing; a roller rotatably mounted in, and peripherally confined by, said housing immediately below and parallel to said elongated opening, said roller having a plurality of longitudinal grooves arranged parallel to the axis of the roller at equi-angularly spaced intervals around its periphery and each adapted to register periodically with said elongated opening and alternately with a delivery slot provided in the peripheral wall of said housing at a position rotationally in advance of said elongated opening and alongside said roller, each of said grooves being recessed inwardly at one and the same end to provide a surface inclined away from the base of the groove and towards the axis of the roller, the junction of the base of the groove and the said inclined surface forming a fulcrum about which a cigarette in the groove may be pivoted by movement inwardly of the roller of that end portion of the cigarette at the recessed end of the roller; operating means for effecting intermittent partial stepwise rotation of said roller; and a spring ejecting finger in said housing opposite that end portion of said roller at which

the recessed ends of said grooves are located, a part of said spring finger being parallel to said inclined surface and adapted to bear on the inwardly movable end portion of a cigarette lying in a groove when that groove registers with the said delivery slot so as to pivot the cigarette about the junction between the base of the groove and the said inclined surface and urge the inwardly movable end portion of the cigarette inwardly until it bears against the said inclined surface and is frictionally gripped between the latter and the part of the spring ejecting finger parallel thereto, and the other end of the cigarette then projecting outwardly of the housing through said delivery slot into a position facilitating the ready gripping of the outer end of the cigarette by an intended user when required for withdrawal of the cigarette from the dispenser.
